1. A device for inflating a mattress, cushion or similar article, comprising a sheath of air impervious but non-elastic material, such as rubberized fabric, having a plurality of tubular compartments, means for dividing the sheath into the compartments, a tube extending through one of the compartments, the tube being filled with springy material, a valve for admitting air into the tube, a safety valve for preventing over-inflation, and a tube extending through the sheath, the tube being filled with springy material.

UNITED STATES PATENT OFFICE

MATTRESS OR THE LIKE

Thomas J. Lineback, St. Louis, Mo., assignor of
one-fourth to Emil J. Morse, Clayton, Mo.

Application July 20, 1940, Serial No. 346,493

2 Claims. (Cl. 5—348)

My invention relates to a mattress, cushion or similar article and more particularly to such an article of the pneumatic type in which enclosed air supplies the necessary yielding quality to provide comfort to the users. Heretofore many kinds of pneumatic mattresses and cushions have been designed. In all of these, as far as I am aware, the compression of air in the article has been depended upon to provide the cushioning effect, it being assumed that such compression would furnish all the resilience that could be desired. I have found, however, that this is not the case as the compression of the air by the weight of the person resting thereon increases its pressure to such an extent that the article becomes uncomfortably rigid.

The main object of my invention is to overcome this difficulty by providing auxiliary yielding means to compensate for the compression of air in the article, thus increasing its resilience.

Another object of my invention is to simplify and improve the details of construction of the article.

In the accompanying drawing which illustrates my invention as applied to a mattress, Figure 1 is a perspective view; Figure 2 is a section taken on the line 2—2 of Figure 1; Figure 3 is a section taken on the line 3—3 of Figure 2; Figure 4 is a view similar to Figure 2 but showing modifications; Figure 5 is a view similar to Figure 3 but showing a different form of compensating means; Figure 6 is a plan view of a mattress formed of independent tubes; and Figure 7 is a section taken on the line 7—7 of Figure 6.

Referring first to Figures 1, 2 and 3, the numeral 10 indicates a sheath of air impervious but non-elastic material, such, for example, as rubberized fabric. This sheath is divided into tubular compartments by means of partitions 11 made of fabric which will allow the free passage of air between the compartments. The mattress is inflated through a valve 12. A safety valve 13 is also preferably provided to prevent over-inflation. To provide auxiliary yielding means to compensate for the compression of the air, I provide a tube 14 extending through one of the compartments. This tube is filled with springy material 15 such as curled hair. While a single tube 14 may provide the necessary compensation, for the sake of symmetry, I prefer to use two tubes, one located at each side of the mattress. The tubes may be rectangular as shown in Figures 1 and 2 or oval as shown in Figure 4.

While in Figures 1 and 2 I have conventionally shown the walls of the sheath 10 as straight, in practice the walls will bulge as shown in Figure 4 when the mattress is inflated, though the amount of pressure required is slight. This results in an objectionable rounded edge. To overcome this, I cement, or otherwise secure, to the edge a reinforcing strip 16 of some material, such as rubber, which while not unduly rigid is

10 sufficiently stiff to maintain a square edge.

In the use of my mattress when the air pressure in the sheath is increased by the weight of the occupant of the mattress, the tubes 14 are caused to collapse against the springy material 15, thus increasing the space within the sheath to compensate for the deflection of the surface thereof caused by such weight. This results in resilience such as cannot be secured by the air alone in the sheath.

20 In Figure 5 I have shown a modified form of compensating means in which the tube 14 extending through the mattress is replaced by a tube 14' which is closed at both ends. One end of this tube is provided with an involute portion 17 between which and the end of the mattress is positioned a coil spring 18. The collapse of this tube 14' is resisted by the air pressure within it which acts against the tension of the spring 18. This spring thus performs the same function as the springy material 15.

25 In some cases it may be found desirable instead of forming the mattress of a single sheath to build it up of a number of smaller sheaths. Such a construction is shown in Figures 6 and 7. 30 The small sheaths 10' are enclosed in an envelope 19 which need not be air tight. The compensating means in such a mattress may be the tube 14 with springy filling, as shown in Figure 7, or the tube 14' and coil spring. The sheaths 10' must inter-communicate so that the pressure will be the same in all of them. This may be accomplished either by a cross pipe 20 having nipples 21 leading to the individual sheaths, as shown in Figure 6, or by passages 40 formed by eyelet-like connectors 22, as shown in Figure 7.

35 I have shown my device as forming a complete mattress for which purpose it is particularly adapted where lightness is a prime consideration. It may, however, be used in lieu of the usual metallic spring structure in inner spring mattresses.

Having fully described my invention, what I claim as new and desire to secure by Letters 45 Patent of the United States is:

1. In a mattress or the like an air-tight sheath of inelastic material, a collapsible tube of impervious material in said sheath resisting variations in air pressure in the sheath caused by weight resting thereon, said tube being open to atmosphere externally of the sheath, a filling of springy material in the tube, and a relief valve limiting the inflation of the sheath to a predetermined pressure.

2. In a mattress or the like, a substantially rectangular sheath of flexible material, said sheath being inelastic and impervious to the

passage of air, a pair of collapsible tubes of air impervious material extending through said sheath adjacent parallel edges thereof, said tubes being open to the external atmosphere at their ends, partitions of air pervious material connecting the upper and lower walls of the sheath between the tubes and extending parallel therewith, a filling of air pervious spring material in the tubes, means for inflating the sheath, and a relief valve limiting the inflation of the sheath to a predetermined pressure.

THOMAS J. LINEBACK.
